UNITED STATES PATENT OFFICE.

FRANK Y. PEARNE, OF LOS ANGELES, CALIFORNIA.

RIVETING AND PUNCHING MACHINE.

1,305,974.

Specification of Letters Patent. Patented June 3, 1919.

Application filed April 5, 1917. Serial No. 160,298.

To all whom it may concern:

Be it known that I, FRANK Y. PEARNE, a citizen of the United States of America, and residing in Los Angeles, in the county 5 of Los Angeles and State of California, have invented a new and useful Improvement in Riveting and Punching Machines, of which the following is a specification.

This invention relates to punching and 10 riveting machines and more particularly to what are commonly called "round seamers" or machines that rivet together sections of riveted pipe, and the principal object is to provide a round seamer that will 15 either punch, lay the lap or rivet without manually shifting the tools.

It is also an object to provide a round seamer that is capable of laying the lap, punching the holes and riveting the rivets 20 by distinct mechanisms separately controlled.

It is a further object to provide a round seamer with auxiliary means to support the free end of a lengthened stake, so that a 25 series of joined sections or one section of greater length than the ordinary cast stake will carry, may be properly connected to form the standard or commercial length of pipe.

30 It is a still further object to provide a round seamer with a plurality of electrical mechanisms that coöperate with the positively acting parts to perform the foot controlled operations.

35 In the drawings accompanying this specification,

Figure 1 is a front elevation of a seamer having a stake of the usual length, with the main features of the invention.

40 Fig. 2 is an end elevation of Fig. 1 viewed from the right.

Fig. 3 is a front elevation on the same scale as Fig. 1 showing the invention as applied to a lengthened stake capable of 45 carrying a section of pipe to twelve feet in length, the pipe on the same being in position for riveting.

Fig. 4 is an end elevation of Fig. 3 viewed from the right side, partly in section, vertically broken.

50 Fig. 5 is also an end elevation viewed from the other end the parts being open for the reception of a section in this and

Fig. 4, the drive of individual type being clearly shown in the latter view. 55

Fig. 6 is a detail in elevation of the pawl mechanism, the cams and bearing being in section.

Fig. 7 is an end view of the above, the bearing being removed to clearly show the engagement of the pawl. 60

Fig. 8 is an elevation of the pawl controlling sleeve, viewed from the inside or engaging face.

Fig. 9 is an elevation of the riveting cam 65 in the same position as Fig. 3.

Fig. 10 is a plan viewed from the under side of the walking beams partly in section to clearly show the fastening means, and

70 Fig. 11 is an elevation of the heads that engage in the recesses of either end of the beams.

Other round seamers require coöperation of the hands, even where a foot control is 75 used, since the tools have to be shifted in the common single head by hand, so that long sections of pipe cannot be easily and cheaply handled, and this invention is especially adapted to round seam the long 80 sections formed on the straight seamer invented by me, and the subject matter of an application now pending in the U. S. Patent Office filed Jan. 29, 1917, and serially numbered 145,301. 85

More specifically in the drawings, numerals are used to designate the parts, 5 representing a base preferably of concrete in which are embedded the parallel and vertically disposed I beams 6-6 providing 90 a support for the short stake 7, secured in a flanged seat 8, the flanges 9 being provided with elongated holes through which the bolts 10 pass to secure the same to the beams adjustably. 95

To control the adjustment, to properly align the dies, screws 11 are threaded into the straps 12 secured to the beams 6, these screws bearing on the edges of the flanges 9.

The stake 7 is provided near its outer end 100 with the dies 15 and 16 over which vertically reciprocate the tools, namely, a punch 17 and a combined lap layer and riveter 18, which are carried by their respective tool holders 19 and 20. The combined tool 105 18, acting as a riveter drives the rivets

placed in the seam from the top, in common manner, to head against the anvil-die 16, the lower end of the tool being cupped as shown in Fig. 4.

5 These tool holders are of a general cylindrical form and are adapted to be reciprocated and guided in vertically disposed bores in a head formed by a plate 21 and the head 22 of a separately cast frame 23, 10 this hollow frame being of sufficient weight but not necessarily as massive as the usual one piece frame, and the standard is provided with a base 24.

15 The punching tool holder 19 is a simple cylindrical slide, having a threaded lower end with a nut to secure the punch in the usual manner, the other being preferably formed of a sleeve 20 interiorly threaded, right and left handed so that the lap layer 20 18 with its left hand threaded shank 25, provided with a key 26 that fits within a keyway in the right hand threaded shank 27; may be capable of adjustment, by turning the sleeve 20, by means of the knurled boss 28.

25 The upper end of the shank member 27 is swelled above the sleeve 20 to fit the guideway in the head 22, being reduced above this point to form the neck to which the cylindrical head 29 is secured, this latter being embraced by a socket formed in the two part walking beam 30, that is adapted to reciprocate this tool.

30 The punching member is also provided with a head 29, but has its own reciprocating walking beam 31, this and the beam 30 being preferably in contact on their inner faces, and mounted loosely on the same shaft 32, which has bearings in the main frame 40 at 33, that are so placed that they form retaining guides and bearings for the outer faces of the beams 30 and 31.

To reciprocate these beams at the proper times, a short shaft 34 is provided that has keyed thereon a large gear 35 which in turn is geared with a pinion 36 keyed to the shaft of a motor 37 mounted on a shelf secured to the main frame 23, and whereby the shaft 34 is driven continuously.

50 Mounted on the shaft 34 and in line with the beams are two eccentrics 38 and 39, each of which is surrounded with an eccentric strap 40, that are in turn connected to heads 41, embraced in sockets formed in the opposite ends of the beams from the sockets for the heads 29.

The shaft 34 has a boss or enlarged portion on which the eccentrics are loosely mounted, these bosses serving as bearings 60 also for the shafts 42 that connect and form pivots for the pawls 43 and 44, mounted on either side of the bearings for the shaft 34, the outer pawl being narrow and adapted to be operated by a clutch member normally held in contact therewith and thus hold the

wide cam engaging pawl 43 from engagement with the tooth cut in the hardened insert 45 in the eccentric, a spring 46 normally tending to force the pawl onto engagement.

70 The clutch member or rather pawl retainer 48 is freely mounted on the reduced ends of the shaft 34 and each has a recess cut on its inner face as shown in Fig. 8 consisting of an inner annular groove with 75 a periphery 49 and a shorter cam arc 50, that brought onto or over the pawl 43 will throw the pawl into the annular groove and disengage the pawl 44 and allow the eccentrics and their beams to come to rest.

80 The retainer 48 has a pair of cylindrical studs 51 on its outer periphery which are engaged by the yoke 52 on a rocker arm 53 pivoted in a bracket 54 on the main frame, an arm 55 secured to the pivot pin of the 85 crank, being under the tension of a spring 56, surrounding the lift rod 57, this spring bearing against a finger on the frame and being adjustable to normally keep the retainer 90 in engagement and releasing the pawls.

The lift rod is connected to a foot lever 58 through a bell crank pivoted to the outside of the frame, by a rod 61 which is adjustably secured to the arm 62 of the foot lever. The lift rod for the beam 31 is designated 63 and is connected to the foot lever 64 through similar connections to operate the eccentric 39 of the beam 31.

To accommodate the slight transverse movement of the beams, the bearings on the shaft 32 are slightly elongated as shown in Fig. 4, and to take up any slack in the tool carrying members and lift this end of the beam to its highest position, elbows 65 are provided on the upper end of each tool member to receive the tension of a spring 66 located so as to press upwardly from a socket in the head 22.

To provide for seaming a series of short 110 connected sections, or one long section twelve feet in length, the stake is preferably formed up of a flanged sleeve support 70 secured to the I beams 6-6, a pipe or steel cylinder 71 being forced on the sleeve and supporting at 115 its outer end the channeled casting 72, one channel being for the riveting block 74 and a passage way for its rod, and a lower passage for the rod 75 secured to the bridging block 76 carried on an inclined slide 77 on 120 the outer and lower part of the casting.

A belling anvil 78 is also provided, and in line therewith on the upper side are inserted the hardened sleeves 79 and 80, the former acting as a guide for the riveting 125 member 81 and the latter as a die for the punch 17 carried in the punching member 19, these latter being in line, the lapping tool 18 being over the riveting member to act as a backing for the rivet.

These punching and lap laying members are operated by the built up beams 30 and 31 previously described mounted on the frame 23, the parts of the beams being held together by the headed bolts, 67 and nuts 68, the heads and nuts being preferably countersunk to make a free bearing surface of the flat plates.

The operation of the beams and their eccentricities is somewhat different than that for the first construction, the punching and lap laying being controlled by foot levers 82 and 83, these levers being connected to lift rods 84 and 85 by a spring returned rod 86 that passes through the lift rod, a buffer spring 87 taking the thrust, and the spring 88 returning the lever when released.

On each rod 86 is an adjustable contact carrying member, having spring contacts 89 and 90, which are adapted to make contact successively with contact fingers 91, 92 mounted in parallel position on the inside of the frame, the first mentioned being adapted to close the circuit from a battery 25 or other source of electrical energy 93 with a solenoid 94, that through the connections to be described later, slides the bridging block 76 to draw the same in contact with the pipe, and immediately this is set, the other contacts 90, 92, controlling the circuit to solenoid 95, contact to energize the solenoid, draw up the core 96 connected to the bell crank 97 to draw inwardly the block 98 under the slide 99, this latter supporting 35 the threaded stem support 100 of the pivoted saddle 101. A nut 102 is threaded on the stem and key 103 sliding in a keyway in the stem holds the parts in operative relation.

The block 98 is slidably mounted on a 40 grooved and pivoted lever 104, the other end of which is resiliently supported by the leaf springs 105, acting as a safety device to prevent injury to the tools under accidental conditions.

As the outer arm 97 raises, the rod 84 is drawn forward by the continued depression of the foot lever to engage the hook 106 with the cross rod 107 on the crank, to lift the rod and release the pawl connections to operate 50 the beam and reciprocate the tools in the proper timing.

The bridging block is formed preferably of a sliding base 76 connected to the operating mechanism by the rod 75, and a removable block 108 held by screws, a number of these blocks 108 being provided, to form the seat for various diameters of pipe. The rod 75 is connected at its opposite end to a bell crank lever 109, the upper arm of which is 55 provided with a bore to receive the rod, and forms a bearing for a spring 110 acting as a buffer.

The other end of the crank arm pivoted at 111 is connected with the core of the 60 solenoid 94, this solenoid being connected

to be switched in by the operation of the foot levers 82 and 83.

The third foot lever 112 is provided to control the operation of the riveting block 74, through its connections; first a connecting rod 114 from the arm 115 of the lever 112 to a bell crank 116 pivoted on the frame 6, the other end of this crank being connected by a rod 117 to the rocking arm of a yoked member similar to that described 75 for the walking beams, the clutch sleeve being designated 119 and the continuously driven gear 120 freely mounted on the shaft, is driven by a pinion 121 on the end of the main shaft 122.

The gear 120 and the mechanism connected therewith are free on the shaft 123, flanged and provided with bearings in the frame numbered 124 on the frame 6, and keyed to this shaft is the cam 125 engaging 85 with a roller 126 mounted in a gimbaled frame 127 this frame being supported in the yokes 128 of the pivoted member provided with the spaced arms 129, to allow movement of the rod 75; across which arms 129 is the 90 pin 130 to which the end of the rod 131 is secured, the other end being adjustably connected with the riveting block 74, bearing on a hardened plate in the casing.

To drive the various mechanisms an individual electric motor 134 is mounted on a shelf 135 secured to the frame 6, which motor through a train of gears 136 drives the shaft 122 continuously at suitable speed, this shaft from a bearing 137 extends to a 100 bearing 138 on the frame 23, and has keyed adjacent thereto the pinion 139 meshing with the large gear 35 keyed to the beam operating shaft 34.

The operation will be readily understood, 105 the routine being in the following sequence, starting with the machine in the receiving position as Figs. 1 and 4 a pipe section 140 is slipped on the stake 71, then a section 141 supported in a suitable sling, not shown, is 110 belled on the anvil 78 and forced over the adjacent end of the section 140 the required distance, then sliding the lap under the lap layer 18 the depression of the lever 82 slides the block 76 and its removable block 108 115 to hold the pipe, the saddle 101 is raised to support the end of the stake and pipe, the operator's hands being free to guide the pipe, and the further depression of the foot lever 82 releases the pawl retainer 48 for the eccentric 38, the beam 30 is operated to depress the laplayer, the release of the lever reversing the operations to allow the pipe to be turned to a new position, or shifted under the punching tool 17, when the operation of 125 the foot lever 83 again moves the block 74, lifts saddle 101 and supports the same against the action of the released punch, the whole forming an auxiliary stake supporting member.

After the punching the sling is hoisted to lift the sections as shown in Fig. 3 with the section 141 tight against the laplayer 18 the lower and inner surface of the section 140 bearing against the proper sized block 108, then depressing the lever 112 with foot, the contacts 142 and 143 immediately contact to energize solenoid 95 lift the saddle 101 to clamp the pipe between said saddle and block 108 and thus support the pipe and stake, the further action releasing the retainer 119 throwing into action cam 125 to slide the riveting block to the left and force the riveting member 81 to contact and head 15 the rivet backed by the recessed laplayer 18.

What I claim is:

1. In a machine of the class described, in combination with a stake supporting member, of a stake mounted thereon, and extending 20 into the operating zone of a punching and riveting carrying member, a punching and riveting carrying member independent of said stake supporting member, having the operating parts separately controlled 25 and means to separately control said punching and riveting members.

2. In a machine of the class described, the combination of a pipe supporting stake, a punching member, a riveting member and 30 walking beams to operate said members separately.

3. A punching lap laying and riveting machine, comprising a pipe supporting member, a punching member, a combined 35 laplaying and riveting member, operating means to operate each of said members, and means to separately control the operation of said members.

4. In a machine of the class described, in 40 combination with a stake supporting member, of a stake mounted thereon, a yieldably supported auxiliary stake supporting member, and means adjacent to said auxiliary stake supporting member to separately 45 punch and rivet material supported on said stake and said auxiliary stake supporting member.

5. In a machine of the class described, in 50 combination with a stake supporting member, of a stake mounted thereon, and extending into the operating zone of a punching and riveting apparatus, a movable auxiliary stake supporting member adjacent said apparatus, means to move said auxiliary stake 55 supporting member, a punching and riveting apparatus provided with operating members separately controlled and means to connect either of said apparatuses with said means to move said auxiliary stake supporting member.

6. A punching, laplaying and riveting machine, comprising a pipe carrying member, a support therefor, a punching member, a laplaying member, a riveting member, 65 operating means to operate each of said

members, means to separately control the operation of said members and an adjustable auxiliary support for said pipe carrying member.

7. In a machine of the class described, the 70 combination of a supporting stake formed of hollow members, a punching member, a riveting member, means to operate said punching and riveting members, and a movable riveting block slidably mounted in 75 said stake.

8. A punching and riveting machine comprising a stake carrying member, a stake formed of a plurality of hollow sections mounted on said stake carrying member, a 80 riveting and punching apparatus adjacent one of said sections, a slidable block mounted in said stake, and separately controlled means to operate said punching and riveting apparatus, whereby it is not necessary 85 to move said block to operate said punching apparatus.

9. A riveting machine comprising a stake supporting frame, a stake having one end supported in said frame, an auxiliary frame, 90 a riveting member mounted on said auxiliary frame, walking beam operating means for said riveting member, a backing member and means to control said riveting member and said backing member.

10. A riveting machine comprising a stake supporting frame, a stake having one end supported in said frame, an auxiliary frame adjacent the other end of said stake, a riveting mechanism mounted on said 100 auxiliary frame, walking beam means to operate said riveting mechanism, and a movable auxiliary stake supporting member adapted to act in conjunction with said riveting mechanism.

11. A punching and riveting machine, comprising a frame, a stake, riveting and punching members, a slidable pipe clamping member, rocking beam members to operate 110 said punching and riveting members, and means to control and operate said rocking beam members and said pipe clamping member.

12. A punching and riveting machine comprising a frame a stake carried by said frame a pipe clamping member mounted on said stake, a frame provided with riveting and punching members reciprocatingly mounted in said frame, walking beams to operate and reciprocate said members, 115 means to operate said beams, and means to control the operation of said beams.

13. A riveting machine comprising a frame a riveting member provided with threads and a tongue, a coöperating member 125 provided with a threaded portion threaded reversely to said other member, and having a recess for said tongue, a sleeve interiorly threaded to receive said members and engage the same in operative and adjustable 130

relation and means to reciprocate said sleeve.

14. A punching and riveting machine comprising a plurality of separate frames, a stake mounted on one of said frames of such length as to accommodate long lengths of material, riveting and punching members mounted on the other of said frames over the free end of said stake, rocking beam

members to reciprocate said riveting and 10 punching members over said stake, cam members to operate said rocking members, means on each of said frames to operate said cam members, and means to control the operation of said means to operate said 15 cam members.
